UNITED STATES PATENT OFFICE.

ALBERT M. PIGEON, OF NORRISTOWN, PENNSYLVANIA, ASSIGNEE TO WILDMAN MFG. CO., OF NORRISTOWN, PENNSYLVANIA, A CORPORATION OF PENNSYLVANIA.

NEEDLE-CYLINDER FOR KNITTING-MACHINES.

1,220,887.

Specification of Letters Patent. Patented Mar. 27, 1917.

Application filed June 6, 1916. Serial No. 101,986.

To all whom it may concern:

Be it known that I, ALBERT M. PIGEON, a citizen of the United States, residing at Norristown, Pennsylvania, have invented 5 certain new and useful Improvements in Needle-Cylinders for Knitting-Machines, of which the following is a specification.

The invention relates to knitting machine needle carriers, circular or straight, in which 10 the needle grooves are provided by walls that may be tempered steel strips inserted in shallow slots formed in the carrier. Various means have been heretofore employed for holding such walls in place, such as en- 15 gaging the ends of the walls, specially shaped for the purpose, with clamping plates, rings and shoulders, which are de- signed to hold the needle walls firmly in the bottom of the slots, and against endwise 20 movement, the intermediate portion of the walls simply resting in the grooves without being fastened other than at their ends.

My invention contemplates holding the walls rigidly at various, or all points 25 throughout their length by a system of swaging, expanding, and compressing the metal of the carrier, between the needle walls.

The invention consists in the features 30 and combination, and arrangement of parts hereinafter described and particularly pointed out in the claims.

In the accompanying drawings;

Figure 1, is a face view of a needle cylinder with a few walls represented in connection therewith, it being thought unnecessary to illustrate the walls all around the cylinder.

Fig. 2 is a sectional view of a part of a 40 cylinder with walls inserted therein, with the walls tightened by compressed and expanded metal between the walls.

Fig. 3 is an exaggerated view of needle walls showing the walls in place and the 45 staggered compressed areas of the needle carrier, for holding the needle walls tight in the shallow grooves.

Fig. 4 is a view of the tools or implements that satisfactorily effect the swaging or 50 compressing of the metal in staggered relation in the needle carrier.

Fig. 5 is a sectional view of a desirable 55 form of a needle cylinder with the walls in place, arrows indicating the compressed, or swaged portions.

Fig. 6 is a fragmental view of a needle carrier of the straight bar type, showing the walls in place, and arrows pointing to the swaged metal areas for holding the walls tight in their grooves.

Fig. 7 shows leaning walls that are im- 60 properly tightened by staking or swaging.

Fig. 8 illustrates generally appliances by which the swaging can be accomplished.

In carrying out the invention I form 65 shallow grooves in the needle carrier approximating in width the thickness of the walls which are to be held therein, say for instance, the wall is intended to be .022 of an inch in thickness and the groove to 70 receive it is calculated to be from .022 $\frac{1}{4}$ up to say .023 of an inch in width. The wall when inserted may be clamped to the needle carrier at its upper and lower ends in any suitable way.

It has been demonstrated in practice that the grooves for the inserted walls are likely to vary from the exact size desired, due to saws cutting a wider slot than intended, or narrower than desired, due to wear of the 80 saw. Needle walls of exact thickness are difficult to make. Variations of .001 to .002 in thickness frequently occur.

Therefore it is not practicable to attempt 85 to make the walls and slots of any exact size, to avoid looseness of the wall in its slot. Clamping the walls at both ends does not prevent the walls from having some looseness sidewise in the grooves. This slight movement develops more looseness in 90 time, until a point is reached where the wall is too loose to be practical or opera- tive, and in the usual practice the machine operator replaces the loose wall with a new 95 one slightly thicker.

By the present method the walls are tightened the whole length of the wall, and less care is necessary in making the slots, and the walls. By the improved method, 100 looseness of the wall in the slot, when the parts are assembled, is of no consequence as the metal is afterward expanded and compressed between the walls of the carrier which tightens the wall without crowding when swaged by the new system.

I have found that walls tightened by so called "staking" or swaging all along the walls, tends to make the walls lean over progressively as shown in Fig. 7, and destroy 110 the correct spacing of the cylinder, and is

2
objectionable in other ways. The present system of swaging does not tend to lean the walls progressively while they are being swaged one after another.

5 As shown in Fig. 1 the needle guiding walls may be held in the cylinder grooves at their upper ends by interengaging parts as at A and at their lower ends the walls may be held by a clamp ring B.
10 At intermediate points *a* along the length of the needle wall I compress or swage the metal of the needle carrier, which is exposed between the walls *b* and which is sufficiently soft to allow this, by any suitable instrument so that as shown in Figs. 2, 3, 5 and 6 the metal will be pressed laterally and will thus firmly grip the inserted wall. One form of implement which may be used for this purpose is shown in Fig. 4, consisting of a plate 20 or bar having points or projections 5' spaced at suitable distances apart. This plate or bar may be of substantially the same thickness as the width of the space between adjacent inserts so that the projections 5' when resting on the face of the needle carrier will extend substantially over the entire width of the metal of the carrier between the inserted walls. Now upon delivering a blow upon the bar or plate 5, 25 the metal will be depressed as indicated at *x*, Fig. 2, and will be caused to press laterally and grip the inserted wall. One of the implements, as 5, shown in Fig. 4 is used in one space between the inserted walls and the other implement 6, shown in said figure is used in the next space between the walls and so on among all the grooves of the needle carrier.

40 Because of the relative spacing of the projections 5' and 6' on the two implements, the swagings will occur in staggered relation in the carrier so that considering one of the inserted walls in relation to the swaged spots or portions it will be seen that these 45 spots are located first on one side of the wall, then on the other side in staggered relation, each swaging on one side lying opposite a plain unswaged portion of the carrier on the other side of the inserted wall. Each wall 50 therefore will be pressed by the swaged portions of the carrier wall first in one direction, and then in the other so that theoretically the wall will assume a sinuous formation although in effect and practice, this 55 sinuosity is not appreciable and will not interfere with the perfect guidance of the needle stem, but will serve to hold the needle wall closely in its groove being pressed against both walls, first in one direction and

then in the other. By this construction the 60 inserted walls will be held firmly throughout their length.

They may be removed however, by applying pressure to them longitudinally, for which purpose each of the walls is provided 65 at its lower portion and in the edge thereof, with a notch 7 and by placing a suitable implement, as a punch, in this notch and at a slight angle to the plane of the edge, the wall can be forced out of the groove by applying 70 mallet or hammer blows to the upper end of the punch or implement.

A new wall can be inserted and the spots already swaged will serve to grip it, as the groove has been forced to the exact width 75 required.

In Fig. 2 the heavily shaded cross hatching indicates diagrammatically the portion of the metal which is more or less affected by the swaging of the metal of the needle carrier, this affected area extending substantially to the bottom of the groove.

By swaging in spots as described above, the inserted walls will be gripped firmly and yet they may be removed and replaced.

85 Further, this spot system of swaging maintains the carrier of the prescribed general formation and spacing and the general line of the insert is maintained straight.

In Fig. 8 I show an arbor at C on which 90 the cylinder, if this is the form of needle carrier employed, is mounted for indexing and D represents a press or ram to apply power to the swaging implement which is shown in position to receive the pressure.

95 What I claim is:

1. A needle carrier having needle guiding walls inserted in grooves therein, the metal of the carrier between the adjacent walls being swaged in spots inwardly and 100 throughout an area from wall to wall to hold both walls in place.

2. A needle carrier having walls inserted in grooves thereof, the metal of the carrier being upset in spots first on one side of any 105 given wall and then on the other, the swaged spots on one side of the wall being opposite unswaged portions on the opposite side of the wall, substantially as described.

3. A needle carrier having walls inserted 110 in grooves thereof, the metal of the carrier between the walls being pressed inwardly in spots to hold the walls in place, said spots being in staggered relation throughout the needle carrier, substantially as described.

115 In testimony whereof, I affix my signature.

ALBERT M. PIGEON.
